[57] CLAIM

The ornamental design for a smocking machine assembly, substantially as shown and described.

DESCRIPTION

FIG. 1 is a top perspective view of a smocking machine assembly showing our new design;

FIG. 2 is a rear elevational view thereof;

FIG. 3 is a bottom perspective view thereof;

FIG. 4 is a cross-sectional view thereof taken along line 4—4 of FIG. 3 with portions omitted for ease of illustration;

FIG. 5 is a cross-sectional view thereof taken along line 5—5 of FIG. 3 with portions omitted for ease of illustration;

FIG. 6 is a cross-sectional view thereof taken along line 6—6 of FIG. 3;

FIG. 7 is an end elevational view of the spool tray as seen along line 7—7 of FIG. 3 and shown separately for ease of illustration; and

FIG. 8 is a cross-sectional view thereof taken along line 8—8 of FIG. 3 with portions omitted for ease of illustration.

FIG. 1
